ENDPIECE FOR STRINGERS OF SEPARABLE
FASTENERS

Albert Süsskind, Berlin, Germany

Application October 15, 1937, Serial No. 169,297
In Germany October 24, 1935

8 Claims. (Cl. 24—205)

The present invention relates to endpieces for stringers of separable fasteners and particularly for stringers of that kind which is cut-off in any desired length from endless bands carrying 5 mutually engaging rows of fastener elements.

The end or limiting pieces hitherto used in connection with fastener stringers of the last named kind are usually attached to the stringers by means of teeth, which when the end pieces 10 of substantially U-shaped cross-section are clamped together will penetrate the material of the stringers. These end pieces have the drawback that they are not rigidly connected with the fastener elements on the stringers, so that 15 they by careless fastening may loosen from the latter. The known end pieces also have the drawback that a special tool must be used for bending the same into their position of use.

The main object of the present invention is to 20 do away with the said disadvantages and procure an end piece which can be positively interconnected with the fastener elements proper and be fixed to the stringers without the aid of a tool. The present invention therefore renders it possible to deliver interconnected fastener strips of 25 great length to the consumers, and leave it to them to divide the strips as it may be required, and to finish the fastener pushing the fastener slide over the rows of fastener elements and by 30 applying the limiting or end pieces without the use of any tool.

The limiting or end pieces according to the invention, which are pushed upon the severed ends of the interconnected fastener strips carrying the 35 fastening elements are in contrast to the known limiting or end pieces equipped with teeth or lugs, which, when the sleeve-shaped limiting or end pieces is applied, resiliently and self-locking will snap into the spaces between the fastening elements on the stringers. The open side of a sleeve-shaped end piece is simply pushed over the severed end of the stringer in question and the end piece is thus not connected with the stringer itself 40 but is only coupled to the fastening elements on the stringer, by the teeth or projections which engage the spaces intermediate the fastening elements on the stringer.

Some embodiments of separable fastener strips and limiting or end pieces according to the invention are illustrated by way of example in the accompanying drawings.

Fig. 1 is a front elevational view of a partly opened fastener strip, with the fastener slide showing two forms of outer end pieces or top 55 stops and an inner end piece or bottom stop,

Fig. 2 is a developed plan view of the end piece or top stop shown on the left side of Fig. 1,

Fig. 3 is a developed plan view of a modification of the top stop shown in Fig. 2,

Fig. 3a is a perspective view of the form shown in Fig. 3,

Fig. 4 is a developed plan view of the end piece or bottom stop shown in Fig. 1,

Fig. 5 is a developed plan view of an end piece or top stop of the type shown at the right of Fig. 1,

Fig. 6 is a vertical sectional view of the top stop shown in Fig. 5 on a slightly larger scale,

Figs. 7 and 8 show a developed plan and side elevation of still another embodiment of an end 15 piece for the opened end of a fastener strip or a top stop,

Fig. 9 is a perspective view of a modified form of bottom stop or an end piece for application to a closed end of a fastener,

Fig. 10 is a developed plan of a further modified form of bottom stop,

Fig. 11 is a perspective view of a form of end piece adapted for use solely on fastener strips of the type which do not require the use of fastener 25 end sections,

Fig. 12 is an elevational view of a still further modified form of end piece or top stop,

Fig. 13 is an elevational view of a further modified form of end piece,

Fig. 14 is a developed plan of a still further modified form of end piece,

Fig. 15 is an elevational view of the form of end piece shown in Fig. 14,

Fig. 16 is an elevational view of the form shown in Fig. 15 applied to the fastener element, and

Fig. 17 is an elevational view of a still further modification showing the top pieces cooperating with the slider of the fastener when the holding parts of the top pieces are angularly arranged 40 to secure the stringer ends.

In Fig. 1, which shows a partially open fastener strip without slide, 1 and 2 denote the fastener stringers, the conventional fastening elements 3 and 4 of which are in mutual engagement, when a length is severed from a moving fastener band.

The free outer ends of the stringers 1 and 2 carry end pieces 5 and 6, respectively, which limit the strokes of the fastener slide, and which by means of bridges or noses engage the fastening elements 45 (Figs. 1 and 2).

To the ends of the members 5 and 6 remote from the fastener stringers 1 and 2, outer stringers 7 and 8, respectively, without fastening elements, are connected. The connection is formed by projections, teeth or the like on 55

the pieces 5 and 6, which penetrate the material of the outer stringers 7 and 8.

At the closed inner end of the fastener strip a limiting or end piece 9 common for both stringers 5 is arranged, which, after it has been pushed over the conventional fastening elements 3 and 4, with its projections or fingers engage the spaces intermediate the fastening members, and hereby is self-lockingly connected with the inner stringer 10 ends 10, 10', which carry no fastening elements.

Fig. 2 shows the form of the end piece 5, also shown in Fig. 1, for fastening elements of the so-called T-type. This end piece has two openings 11, 11', the walls 11" and 11''' engage the necks of the T-shaped fastening elements. The end piece 5 is bent into U-shape about the dashed lines 12, 12'. The one end of the end piece 5 is formed with projections 13, 13', which are right-angularly bent and serve for connecting the end piece with the outer stringers 7 shown in Fig. 1. When the end piece is bent into U-shape, it is closed by the teeth 14 engaging correspondingly formed cavities 15 in the opposite edge of the end piece.

Fig. 3 shows another form of an end piece for the open end of a fastener strip. The end piece is bent into U-shape about the lines 16, 16'. Projections 17 and 17', which after the folding are right-angularly bent, serve as guides along the fastening elements. Other guides are formed by the members 18 and 18', which before use also are right-angularly bent. After the end piece has been pushed over the rows of fastening elements, the projecting parts 19 and 19' at the upper end 35 of the piece will engage the space intermediate two fastening elements, whereby the piece is securely held in position.

For the attachment of the stringer sections 10, 10', which do not carry any fastening elements, the end piece may at its lower end be formed with points 20 or teeth 21 adapted, after having been right-angularly, to penetrate the material of the stringers. After the bending, the end piece may for instance be held together by means of lateral teeth 22, adapted to engage recesses 23 in the opposite side of the end piece. Instead of this arrangement a rivet may be used, which after the bending is inserted through the holes 24 and 24'.

Fig. 4 shows an end piece for the closed end of the fastener strip similar to the end piece 9 shown in Fig. 1. This end piece consists of two plates 26 and 26', which are interconnected by means of a bridge 25, and are bent into U-shape about this bridge. Deformation of the folded end piece 55 may be avoided by means of projections 27, adapted to engage recesses 28. Adjacent the bridge teeth 29 and 29' are formed, which serve for the attachment of the end piece to the stringer ends which do not carry fastening elements. For the same purpose also lateral teeth 30 and 30' may be used, which before use are bent right-angularly to the plates 26, 26'. After the folding of the end piece the projecting 60 tongues 31, 31' and 32, 32' on the plates 26 and 26', respectively, are bent rectangularly to the said plates, and when the end piece is pushed over the rows of fastening elements, these, tongues will engage the spaces between the fastening elements, on the outer sides of the rows, whereby the end piece is securely held in position.

The end piece shown in the Figs. 5 and 6 is before use folded into U-shape about the lines 33 and 33'. The end piece is formed with tongues 75 34, 34', stamped out in the sides of the piece,

and at the ends of these tongues hooks 35 and 35' are formed, which, when the end piece is pushed over the rows of fastening elements, will snap into the spaces intermediate the fastening elements.

The Figs. 7 and 8 show an end piece adapted for use at the open end of a fastener strip. As shown in Fig. 7 this end piece has lateral arms 36 and 36' with inwardly projecting, hook-shaped ends 37 and 37', and an intermediate arm 38 10 which, as indicated in Fig. 8, has an inwardly and downwardly inclined tongue 38'. When the end piece is applied to a fastener strip, the tongue 38' will snap into the hole of a fastening element 39 and the hooks 37 will engage the spaces intermediate the fastener elements.

An end piece, resembling that shown in the Figs. 5 and 6, but designed for use at the closed end of a fastener strip, is shown in Fig. 9. This end piece is formed with tongues 40 and 40', the 20 ends of which are hook-shaped and adapted to engage the two rows of fastening elements.

Fig. 10 shows an end piece for the closed end of a fastener strip, resembling that shown in Figs. 7 and 8 for the open end of a fastener strip. This 25 end piece consists of two plates 42, 42', which are interconnected by means of a bridge 41 and before use are bent about the edges of this bridge. The plates 42, 42' have arms 43, 43' and 44, 44', respectively, the ends of which are hook-shaped 30 and adapted, when the folded end piece is applied to the closed end of a fastener strip, to engage the spaces between the fastening elements and lock the end piece to the latter.

Fig. 11 is a perspective view, showing an end 35 piece for the closed end of a fastener strip which has no stringer end sections without fastening strips (shown at 10, 10' in Fig. 1). The plate-shaped parts 45, 45' of this end piece, which are interconnected through the bridge 48 about 40 which they are bent, and at their front ends have lips 46, 46' and 47, 47' adapted to engage the spaces intermediate the fastening elements, terminate at the bridge 48 and have thus no projections or the like for attachment to stringer end 45 sections not carrying fastening elements.

Fig. 12 shows schematically an end piece for the closed end of a fastener strip. To this end piece the inclinedly cut-off stringer end sections 50 and 50' without fastening elements are attached. Along the lines 51 and 51' these end sections are coated with an adhesive layer, in order to facilitate the connection with the main stringer sections carrying the fastening elements. The last named stringer sections hereby overlap 55 the adhesive-coated ends of the sections 50 and 50'.

From Fig. 12 it can be seen, how far the fastener slide 52 will slide over the end piece before it is arrested.

The end piece 53 shown in Fig. 13 is designed for use at the closed end of a fastener strip which has no stringer sections without fastening elements. This end piece has two inwardly yielding tongues 54 and 55, which, when the end piece 65 is applied, will engage spaces intermediate the fastening elements and automatically lock the end piece 53 in the proper position. The bridge member of this end piece is formed with lateral projections 56 and 56', which at their edges are 70 formed with rows of teeth 57 and 57' or the like and surround the severed ends of the stringers without fastening strip whereby fringing of the stringer ends is prevented.

The endpiece for the end of the fastener strip 75

shown in Figs. 14, 15 and 16, which also has U-shaped edges 58 and 58', is formed with a rigid nose 59. The stringer end section 60 without fastening strips is fixed to the endpiece by means 5 of a rivet 61, which simultaneously holds the parts of the endpiece together after the latter has been folded into U-shape. When this endpiece is applied to the open-fastening elements carrying 10 end of the fastener strip (see Fig. 16), the rigid nose 59 will first press the fastening elements 62 downward and slide past the same, whereupon these fastening elements will snap back into their original position and hold the endpiece securely in the chosen position.

15 The endpieces shown in Fig. 17 are substantially of the same form as that shown in Fig. 14. The parts 63, 63', of the endpieces located on the fastening elements form an angle with the parts 20 64, 64' of the same to which the stringer sections 64 and 64' are attached which carry no fastening elements. Due to this arrangement, the parts 63, 63' will without difficulty slide into the fastener slide, which is indicated in dot-and-dash-lines at 65, and when the strip is closed, the parts 25 64, 64' carrying the stringer ends to which no fastening elements are fixed, will not, as otherwise, point outward away from each other, but will lie adjacent each other in parallel relation. This gives a fastener of good appearance, which 30 closes perfectly.

Instead of this arrangement the stringer sections 64 and 64' may be pivoted to the endpieces 35 63 and 63', so that they easily may be brought into the proper position when the structure is closed.

The fastener elements carrying stringers may be marked with arrows or the like according to Fig. 1, for the purpose to show the direction in which the slide must be moved over the stringers, and on which end the corresponding endpieces must be applied.

I claim:

1. An endpiece for stringers of slide actuated

fasteners, which stringers have each a continuous straight row of spaced fastening elements, said endpiece consisting of walls connected by an apex so as to give to said endpiece a U-shaped profile, and being adapted to be pushed along 5 said row to a position overlapping the outermost fastening elements of said row, said endpiece being provided, with at least one anchoring member inclining inwardly toward said fastening elements, said member presenting a pawl-like tooth having 10 a gently inclined cam face, adapted to slip over said fastening elements, and a sharply inclined locking face, adapted to engage firmly said fastening elements for locking the endpiece against longitudinal movement in one direction along 15 said fastening elements.

2. An endpiece as in claim 1, in which said tooth is formed by the end of an elastic tongue connected with said end piece.

3. An endpiece as in claim 1, which consists of 20 elastic material, and in which said tooth is formed by the end of a tongue, integral with said endpiece.

4. An endpiece as in claim 1, in which at least one wall of the U is provided with two tongues, 25 each having an anchoring tooth, the sharply inclined end faces of said tongues being offset longitudinally relative to each other.

5. An endpiece as in claim 1, which consists of 30 elastic material, and in which each wall of the U is integral with a tongue provided with said tooth, the teeth of said tongues facing each other.

6. An endpiece as in claim 1, in which said tooth is provided at the apex of the U.

7. An endpiece as in claim 1, in which the apex 35 of the U and at least one of the walls of the U are each provided with an anchoring tooth.

8. An endpiece as in claim 1, in which each wall of the U is provided with two anchoring tongues facing each other, the sharply inclined 40 end faces of said tongues being offset longitudinally relative to each other.

ALBERT SÜSSKIND.
